United States Patent Office.

SAMUEL C. THORNTON, OF MOORESTOWN, NEW JERSEY.

Letters Patent No. 79,163, dated June 23, 1868.

IMPROVED RAILWAY-SIGNAL.

The Schedule referred to in these Letters Patent and making part of the same.

TO ALL WHOM IT MAY CONCERN:

Be it known that I, SAMUEL C. THORNTON, of Moorestown, county of Burlington, and State of New Jersey, have invented a new and useful Improvement in "Railway-Signals;" and I do hereby declare that the following is a full, clear, and exact description of the construction and operation of the same, reference being had to the accompanying drawings, making a part of this specification, in which—

Plate 1 is a perspective view of my railway-signal.

Plate 2 is a front elevation of same.

The object of my invention is to construct a railway-signal, so arranged, as hereinafter described, that it will do away with flagmen, and lessen the danger at crossings, and warn parties on roads crossing railways of any approaching train. It is especially adapted to streets that cross railways, where the approaching trains are obstructed from view by houses; or, where the railway passes through woods, deep cuts, tunnels, or around curves, the usual signals on railways, by whistle, bell, &c., cannot always be heard, and are often neglected to be used by the engineer.

To enable others skilled in the art to make and use my invention, I will now proceed to describe its construction and operation.

G S, plate 1, represents the ground-surface of the road which crosses the track, at a short distance from and parallel with the track, and on each side of the road I place two upright posts P and P', which are set in the ground at sufficient depth to secure them firmly in place. I then brace them at the top by cross-piece C P, the posts P and P' being set above the ground at sufficient height to admit of the passage of any vehicle, such as a load of hay, &c., &c. At a short distance below cross-piece C P, I place a roller, C R, having its bearings in posts P and P'. On the end of the roller C R, which passes through post P', is placed a bevel-gear wheel, B V. On the outside of P', and near the top and bottom, are placed iron arms, A and A', provided with bearings, in which runs the vertical shaft S. On the end of shaft S, which passes through arm A, is placed a bevel-gear wheel, B V', which works in bevel-gear wheel B V. On the opposite end of shaft S, or the end which passes through A', is placed bevel-gear wheel B V''.

The sleepers 1, 2, 3, 4, 5, and 6, on which track R L is laid, are of the ordinary size, while sleeper 7 is made longer, and extends out to post P', on the under side, and working in the centre of sleepers 2, 3, and 7, is placed a rack, R. In the centre and on top of sleepers 4 and 5 are placed bearings B and B', in which works rack R'. Both of said racks are provided with arms D and D', which extend a short distance above the rails R L. Running on a line with sleeper 7 is a shaft, S', on which is placed a pinion, P N, working in the racks R and R', and a bevel-gear wheel, B V''', which works on B V'', said shaft being guided and held in place by arms A'' and A''. Shaft S' can be continued, if desired, on the opposite side of the road, to operate a similar arrangement.

On the roller C R is secured a curtain, C, made of canvas, or any other suitable material, having on its end an iron rod, of sufficient weight to give it a proper tension.

Now, to operate my invention, it is necessary that the cow-catcher of the locomotive should be provided with a bumper, H, made with a toggle-joint, (as shown on car in plate 2,) back of which is secured a spring, S P, of sufficient elasticity to keep it set. This bumper can also be applied to the rear end of the car, so as to operate the curtain when backing.

In building a full-size machine, the rack R will work in bearings placed on the top of the sleepers, and also will be made with a slight inclination, in order to enable it to work on pinion P N. The rack R' will also be provided with similar bearings.

The road which crosses the track should be covered with tight-fitting planks, so as to guard against any dirt from passing through and on to racks R and R'.

Operation.

We will now suppose a train is approaching, and the racks R and R' are now in the position, as shown in plate 1. The bumper H on the end of the cow-catcher strikes arm D' of the rack R', and carries it forward, and

turns the shaft S', by means of the pinion P N, and communicates motion to the shaft S, by means of the bevel-gears B V'' and B V''', which again operate the roller C R, and lowers the curtain C, by means of the bevel-gears B V and B V'. It will be seen also by this movement, that the rack R moves to the right, while the rack R' moves to the left; consequently the arms D and D' assume the position shown in plate 2. Arm D' not being able to be pushed any further, in consequence of coming in contact with the bearing on the sleeper, the toggle-joint of the bumper H is pressed back, and passes over the arm D', when it again assumes its proper position by means of the spring S P. The train now having passed over D'; passes on until it meets D, and carries it forward, and consequently moves rack R, which, in turn, moves all the connecting shafts and gearing in the opposite direction, and raises the curtain. This last-named movement leaves the signal set in the manner as shown in plate 1, and is ready for the next approaching train. It will also be obvious that a train coming in the opposite direction from the one described, will act on the curtain in the same manner as hereinbefore shown.

When it is desired, a lantern can be substituted in place of the curtain, to be raised and lowered in the same manner.

The above-described bearings, racks, shafts, and arms are made of iron, or any other material that will answer the same purpose.

Having thus described my invention, its construction and operation, what I claim as new, and desire to secure by Letters Patent of the United States, is—

1. Frame, composed of C P, P, and P', roller C R, and curtain C, bevel-gear'd wheels B V, B V', arm A, shaft S, arm A', bevel-gear'd wheels B V'' and B V''', arm A'', shaft S', pinion P N, arm A''', racks R and R', all constructed, arranged, and operating in the manner as above set forth and described.

2. Racks R and R', with their arms D and D', said racks arranged with or without bearings, and operating in the manner and for the purpose above set forth.

3. Bumper H, with its toggle-joint and spring S P, arranged and operating on arms D and D', in the manner as above set forth and described.

4. A railway-signal, composed of the above-described parts, all combined, constructed, and operating in the manner as above set forth and shown.

SAML. C. THORNTON.
